DESIGN FOR A VIRGIN SHRINE ALTAR

Jean De Lisle, Torrington, Conn.

Application May 22, 1939, Serial No. 85,116

Term of patent 3½ years

To all whom it may concern:

Be it known that I, Jean De Lisle, a citizen of the United States and residing in the city of Torrington, in the county of Litchfield and State of Connecticut, have invented a new, original, and ornamental Design for Virgin Shrine Altars, of which the following is a specification, reference being had to the accompanying drawing, forming part thereof.

Fig. 1 is a front view of the virgin shrine altar, showing my new design.

Fig. 2 is a side view of the same.

Fig. 3 is a rear view of the same.

I claim:

The ornamental design for a virgin shrine altar, as shown.

JEAN DE LISLE.
